R. B. FISHER

LUBRICATION OF SLEEVE PRINCIPLE ENGINES

Filed Dec. 23, 1926

Robert B. Fisher
By Walter M. Fuller

UNITED STATES PATENT OFFICE.

ROBERT B. FISHER, OF DETROIT, MICHIGAN, ASSIGNOR TO SKINNER AUTOMOTIVE DEVICE CO., INC., OF DETROIT, MICHIGAN, A CORPORATION OF CALIFORNIA.

LUBRICATION OF SLEEVE-PRINCIPLE ENGINES.

Application filed December 23, 1926. Serial No. 156,542.

In some cases, in internal-combustion engines or motors of the sleeve-principle or Knight type, it is desirable to provide supplemental lubrication to the upper parts of the movable sleeve or sleeves, especially in those constructions where lubricating oil from around the one or more sleeves is withdrawn or removed through the cylinder-wall below, or in the zone of suction action of, the cylinder intake-port to prevent it from being sucked or drawn into the latter, by reason of the specified sub-atmospheric pressure present there, and uselessly burned in the cylinder.

With this and other advantageous objects in view, the present invention has been provided, a preferred embodiment of which is illustrated in the accompanying drawing, throughout the views of which like reference characters have been employed to designate the same parts.

In this drawing:

Fig. 1 is a fragmentary, central, vertical section through one cylinder of a multi-cylinder, internal-combustion, sleeve-type engine incorporating the features of construction of the present invention, the oil-rectifier being shown on a smaller scale;

Fig. 2 is a fragmentary, horizontal section on line 2—2 of Fig. 1; and

Fig. 3 is a similar, vertical section on line 3—3 of Fig. 1.

Upon having recourse to these views of the drawing, it will be seen that the water-jacketed, engine-cylinder 11 has the usual inlet and exhaust ports 12 and 13, respectively, and inner and outer, ported, reciprocatory sleeves 14 and 15 in the order stated, the piston within the inner sleeve and its connecting-rod not being shown because their constructions and functions are well understood, it being borne in mind that the cylinder, sleeves, and piston are lubricated in any approved fashion.

The cylinder side-wall below and in line or longitudinal alignment with the cylinder intake-port 12 is supplied with an oil-withdrawal port 16 connected to an external, tubular manifold 17 extended horizontally along the sides of, and similarly joined to the corresponding ports of, all of the several engine-cylinders, such manifold being connected by a pipe 18 to an oil rectifier or purifier 19 of known design united by a pipe 21 to the

engine intake-manifold, or other suitable, sub-atmospheric producing means, which supplies the suction for withdrawing the impure oil through the engine-cylinder ports 16, the rectifier having a discharge-pipe 22 for delivering the reclaimed or purified oil back to the engine crank-case for further use, it being understood that the volatile and vaporizable, contaminating ingredients of the impure oil, gasified or vaporized in the rectifier, pass on into the intake-manifold, and are burned in the engine, the distillation or vaporization chamber of the rectifier being heated by an encasing jacket 23, through which a portion of the exhaust gases of the engine pass, if needed to supply the required degree of temperature.

In some cases, such purification of the oil is not required, and, under such circumstances, the rectifier may be omitted, but it and its connections must be replaced by an appropriate pump or other means for producing the required suction and the delivery of the oil at atmospheric pressure.

The outer, reciprocatory sleeve 15 has a slot or port 20 therethrough in register with the cylinder-port 16, and of a length sufficient to maintain constant communication therewith during the travel of the sleeve, such outer sleeve also having around its external, cylindrical surface a number of horizontal, spaced, oil-distributing grooves 24, 24, the upper ones, characterized 25, of which intersect and therefore communicate with such slot or port 20.

The inner sleeve on its outer surface has a number of vertically-separated, horizontal, oil grooves 26, 26 which do not extend all the way around the sleeve, but terminate at the spaced points 27, 28 at the back of the sleeve as viewed in Fig. 1.

Such inner sleeve also has, on its external, cylindrical surface, a similar, upper, horizontal groove 29 beginning at the point 31 and extending almost all the way around the sleeve to the point 32.

Such groove or channel 29 connects with the lower end of an upright groove 33 likewise cut or located in the outer face of the inner sleeve.

A port 34 through the outer sleeve is in longitudinal alignment with the groove 33, and the external face of the outer sleeve has an inclined groove 35 connecting at its lower

end with such port and opening at its top end into the sealing-head compartment of the engine-cylinder.

When, therefore, the port 34 overlaps the groove 33 during the relative travel of the sleeves, the continuous suction at the cylinder-port 16, derived from the sub-atmospheric pressure in the intake-manifold through the rectifier, will be exerted on the sealing-head compartment to withdraw or abstract the contents or a portion of the contents of the latter.

It is desirable to draw some of the oily vapor from the top part of the crank-case of the engine into such sealing-head compartment to assure adequate lubrication of the upper portions of the sleeves, the excess of such oil thus introduced into such chamber being removed by the suction means already described.

To this end, a groove 36, partly inclined and partly straight or vertical, as depicted in Fig. 1, is cut in the outer surface of the inner sleeve, its upper, open end being in constant communication with the sealing-head chamber, its lower end terminating at such a point, as shown, that part of the time it will be uncovered by the chamfered or beveled, lower end 37 of the outer sleeve, and will be covered thereby during the remainder of the time.

When the piston is at the top, dead-center on the firing stroke, that is to say, when it has just completed the compression of the gaseous fuel-mixture, and is about to start down on its explosion stroke, the grooves 35 and 33 are in connection with one another through the port 34 and the contents of the sealing-head compartment are being withdrawn through groove 29, port 20 and the cylinder-port 16 into the rectifier, but, at this time, the port 34 is rapidly receding upwardly from the channel 33, and the connection between them is completely severed when the piston has descended approximately one hundred degrees.

During about the next thirty-five degrees of downward travel of the piston, there is no communication with the sealing-head compartment.

At about this point (one hundred and thirty-five degrees) the channel 36 in the outer surface of the inner sleeve begins to be uncovered by the chamfer 37 of the outer sleeve, thus establishing a connection between the sealing-head compartment and the upper portion of the engine crank-case, and the oily vapor of the latter is sucked through such conduit into the compartment by the partial vacuum therein at the time of establishing such connection, which is accentuated by the combined downward travel of the two sleeves.

Such inflow of oily vapor continues while the piston travels through approximately two hundred and fifty-five degrees, or until the piston is about thirty degrees past top dead-center on the intake cycle or stroke.

At such thirty-degree position of the piston

the channel 36 becomes closed by the chamfer of the outer sleeve.

During the period the piston travels from this three hundred and ninety degree position (thirty degrees beyond top dead-center) to its four hundred and twenty degree position (sixty degrees beyond top dead-center), there is no connection with the sealing-head compartment.

At about this four hundred and twenty degree point, port 34 establishes connection between channels 35, 33 and 32, ports 20 and 16, and the rectifier, thus initiating the suction withdrawal of the fluid contents of the sealing-head compartment, this removal being facilitated and accentuated by the upward travel of the sleeves, which obviously reduces the volume of such compartment.

This lubricant removal or withdrawal continues until the piston reaches approximately its eight hundred and twenty degree position, which is about one hundred degrees beyond top dead-center, being the one hundred degrees first mentioned above.

Hence, the suction removal occurs during about four hundred degrees of travel of the piston, the lubricant inflow into the compartment takes place during approximately two hundred and fifty-five degrees of piston movement, and such compartment is shut off from both connections during two periods of about thirty degrees and thirty-five degrees, respectively, between the breaking and making of the specified connections.

This suction withdrawal of the contents of the sealing-head compartment allows an undesirable pressure, which would otherwise tend to be built up and sealed in such compartment, thus precluding the proper upward travel of lubricating oil around the sleeves, to be exhausted from such chamber, with the resulting avoidance of its objectionable characteristics.

During the descent and consequent displacement of the sleeves, as specified above, the already existing vacuum in the sealing-head compartment is increased, thereby assuring a more efficient flow of the oily vapor from the crank-case thereto through the relatively small sleeve-duct 36.

Were all of the oil thus introduced into the sealing-head compartment permitted to remain therein, it would probably be excessive in amount to effect the needed lubrication of the upper end portions of the sleeves, and, accordingly, it is of advantage to draw off at least a portion of it.

In this connection, it should be noted that the oil is injected into such compartment at one point and is withdrawn at a point roughly one hundred and eighty degrees therefrom, thus causing the oil to travel around the tops of the sleeves, effecting their efficient lubrication.

It will be observed that the groove 36 is lo-

cated between the ends of the oil grooves around the inner sleeve, so that there is no conflict between them or direct connection between them.

5 The suction at the cylinder-port 16 also extracts oil from the grooves 24, 25 and 26 of both sleeves by reason of the presence of the outer sleeve-port 20, and hence it prevents an excess of oil from reaching the cylinder in-
10 take-port 12, as otherwise an undue quantity of lubricant would probably enter the firing chamber through the inlet-port of cylinder and sleeves and be uselessly consumed therein.

This last-specified oil withdrawn makes it
15 desirable to lubricate the sealing-head compartment as stated to compensate for the loss of oil which would otherwise find its way into such compartment along the sleeves.

The extracted oil may be more or less im-
20 pure, and it is purified in the rectifier and re-
turned to the crank-case of the engine in the well-known manner, the air, gases, vapors, etc., in the rectifier flowing through the in-
take-manifold into the cylinders, where they
25 are burned to an economic advantage.

Obviously, many changes may be made in the structure presented and still it would incorporate the fundamental principles of the invention as defined by the appended claims;
30 for example, the source of oil supply need not necessarily be the oily vapor in the crank-case, as other connections may be made with different sources of lubricant-supply.

Furthermore, the intake-manifold suction
35 need not indispensably be employed as the means for withdrawing the oil, since other equivalent means could be readily substituted, and, in some cases, pressures greater than at-
mospheric could be used satisfactorily, in-
40 stead of employing pressures below that of the atmosphere to accomplish the stated re-
sults.

I claim:

1. In an internal-combustion engine, an en-
45 gine-cylinder having intake, exhaust and oil ports, means to apply suction at said oil-port, movable sleeves in said cylinder controlling said intake and exhaust ports, means to move said sleeves, means to contain a lubricant-
50 supply, a conduit connecting the sealing-head compartment of the engine with said lubri-
cant-supply means opened and closed by the movement of at least one of said sleeves, and a conduit adapted to connect said sealing-
55 head compartment with said oil-port opened and closed by the movement of at least one of said sleeves.

2. In an internal-combustion engine, the combination of an engine-cylinder having in-
60 take, exhaust and oil ports, means to apply suction at said oil-port, movable sleeves in said cylinder controlling said intake and ex-
haust ports, means to move said sleeves, means to contain a lubricant-supply, a conduit con-

necting said sealing-head compartment of the engine with said lubricant-supply means, and a conduit adapted to connect said sealing-head compartment with said oil-port opened and closed by the movement of at least one of said sleeves.

3. In an internal-combustion engine, the combination of an engine-cylinder having intake, exhaust and oil ports, means to apply suction at said oil-port, sleeve means in said cylinder controlling said intake and exhaust ports, means to move said sleeve means, means to contain a lubricant-supply, a conduit connecting the sealing-head compartment of the engine with said lubricant-supply means opened intermittently by the movements of said sleeve means, and a conduit adapted to connect said sealing-head compartment with said oil-port opened intermittently by the movements of said sleeve means.

4. In an internal-combustion engine, the combination of an engine-cylinder having intake, exhaust and oil ports, means to apply suction at said oil-port, sleeve means in said cylinder controlling said intake and exhaust ports, means to move said sleeve means, means to contain a lubricant-supply, a conduit connecting the sealing-head compartment of the engine with said lubricant-supply means opened intermittently by the movements of said sleeve means, and a conduit adapted to connect said sealing-head compartment with said oil-port opened intermittently by the movements of said sleeve means during periods of closure of said first conduit.

5. In an internal-combustion engine, the combination of an engine-cylinder having intake, exhaust and oil ports, a lubrication-system, movable inner and outer sleeves in said cylinder controlling said intake and exhaust ports, a conduit adapted to connect the sealing-head compartment of the engine with said lubrication-system, and a conduit adapted to connect said sealing-head compartment with said cylinder oil-port, the movements of said sleeves relative to one another opening and closing said conduits.

6. In an internal-combustion engine, the combination of an engine-cylinder having intake and exhaust ports and an oil-port through its side-wall in substantial alignment with said intake-port, a crank-case containing lubricant, inner and outer movable sleeves in said cylinder having oil grooves, said outer sleeve having a port in register with said cylinder-wall oil-port and in communication with at least some of said sleeve-grooves, said sleeves having a conduit adapted to connect the sealing-head compartment of the engine with its crank-case, the movements of the sleeves opening and closing said conduit, means to establish suction at said cylinder-wall oil-port, and a conduit adapted to connect said cylinder-wall oil-port with said seal-

ing-head compartment, the movements of said sleeves opening and closing said latter conduit.

7. In an internal-combustion engine, the combination of an engine-cylinder having intake and exhaust ports, movable sleeve means in said cylinder controlling said ports, means to move said sleeve means, and means to apply suction to the sealing-head compartment 10 of the engine to remove at least a portion of its contents, said sleeve means having a conduit therein adapted to connect said sealing-head compartment with the crank-case of the engine, the movements of said sleeve means 15 opening and closing said conduit.

8. In an internal-combustion engine, the combination of an engine-cylinder having intake and exhaust ports, movable sleeve means in said cylinder controlling said ports, means 20 to move said sleeve means, said sleeve means having a conduit therein connecting with the sealing-head compartment of the engine and with a port through the engine cylinder-wall, the movements of said sleeve means opening 25 and closing said conduit, and means to apply suction to said cylinder-wall port.

9. In an internal-combustion engine, the combination of an engine-cylinder having intake and exhaust ports, movable sleeve means 30 in said cylinder controlling said ports and having oil passage means, means to move said sleeve means, and means including said oil passage means to introduce lubricant intermittently into the sealing-head compartment 35 of the engine.

10. In an internal-combustion engine, the combination of an engine-cylinder having intake and exhaust ports, movable sleeve means in said cylinder controlling said ports 40 and having oil passage means, means to move said sleeve means, and means including said oil passage means to remove lubricant intermittently from the sealing-head compartment of the engine.

45 11. In an internal-combustion engine, the combination of an engine-cylinder having intake and exhaust ports, movable sleeve means in said cylinder controlling said ports and having oil passage means, means to move said 50 sleeve means, means including oil passage means of said sleeve means to introduce lubricant intermittently into the sealing-head compartment of the engine, and means including oil passage means of said sleeve means to remove lubricant intermittently from said 55 sealing-head compartment.

12. In an internal-combustion engine, the combination of an engine-cylinder having intake and exhaust ports, movable sleeve means 60 in said cylinder controlling said ports and having oil passage means, means to move said sleeve means, means including oil passage means of said sleeve means to introduce lubricant intermittently into the sealing-head 65 compartment of the engine, and means in-

cluding oil passage means of said sleeve means to remove lubricant intermittently from said sealing-head compartment during the periods said lubricant-introducing means is inactive.

70 13. In an internal-combustion engine, the combination of an engine-cylinder having intake and exhaust ports, movable sleeve means in said cylinder controlling said ports and having oil passage means, suction means including oil passage means of said sleeve means to introduce lubricant intermittently into the sealing-head compartment of the engine, and suction means including oil passage means of said sleeve means to remove lubricant intermittently from said sealing-head compartment during the periods said lubricant-introducing means is inactive.

75 14. In an internal-combustion engine, the combination of an engine-cylinder having intake and exhaust ports, movable sleeve means in said cylinder controlling said ports and having oil passage means, suction means including oil passage means of said sleeve means to introduce lubricant intermittently into the sealing-head compartment of the engine, and suction means including oil passage means of said sleeve means to remove lubricant intermittently from said sealing-head compartment during inactive periods of said lubricant-introducing means, the degree of suction of said first suction means being greater 80 than that of the second suction means.

85 15. In an internal-combustion engine, the combination of an engine-cylinder having intake, exhaust and oil ports, means to apply suction to the oil-port, movable sleeves in said cylinder controlling said intake and exhaust ports, means to move said sleeves, and means to contain a lubricant-supply, said sleeves 90 having a conduit connecting the sealing-head compartment of the engine with said lubricant-supply means opened and closed by the movement of said sleeves and a conduit adapted to connect said sealing-head compartment 95 with said oil-port.

100 16. In an internal-combustion engine, an engine-cylinder having intake, exhaust and oil ports, means to apply suction at said oil-port, movable sleeves, in said cylinder controlling said intake and exhaust ports, means to move said sleeves, and means to contain a lubricant-supply, said sleeves having a conduit connecting the sealing-head compartment of the engine with said lubricant-supply means opened and closed by the movement 105 of at least one of said sleeves and a conduit adapted to connect said sealing-head compartment with said oil-port opened and closed by the movement of at least one of said sleeves.

115 17. In an internal-combustion engine, the combination of an engine-cylinder having intake, exhaust and oil ports, means to apply suction at said oil-port, movable sleeves in 120
